J. L. TANDY

TOP OR COVER

Filed June 25, 1923

Fig.2.

INVENTOR

John Lewis Tandy

UNITED STATES PATENT OFFICE.

JOHN LEWIS TANDY, OF KANSAS CITY, MISSOURI.

TOP OR COVER.

Application filed June 25, 1923. Serial No. 647,739.

To all whom it may concern:

Be it known that I, JOHN LEWIS TANDY, a citizen of the United States, and a resident of Kansas City, in the county of Jackson 5 and State of Missouri, have invented new and useful Improvements in Tops or Covers, of which the following is a specification.

The invention relates to improvements in tops, or covers, of the type adapted to reduce 10 temperature by the evaporation of moisture; and the object of the improvement is, to provide an inexpensive, and effective, removable top or cover for various receptacles, such as jars, pails, baskets, and numerous other 15 portable receptacles where their contents are desired to be kept cool and fresh, or under the protection of a cover, to exclude dirt and the many forms of animal life, to prevent certain kinds of contents from 20 splashing out, or spilling out, while the receptacle is being ported about; and to provide a top or cover properly adapted to be applied to receptacles equipped with my improvement in "cooling devices," (as mentioned in the specification for same, in my 25 application for United States patent, allowed February 5, 1923), referred to hereinafter.

Referring to the accompanying drawing 30 illustrating the improved top or cover, as adapted to be applied in some of its various forms;

Figure 1 is a perspective view illustrating 35 a pail with the improved top or cover applied over its top portion;

Figure 2 is a perspective view illustrating 40 the improved top or cover in a modified form applied to a basket;

Figure 3 is a sectional view of the cover 45 applied over an ordinary receptacle in connection with the said "cooling device";

Figure 4 is another sectional view of the 50 cover applied over an ordinary metal top on a receptacle;

Figure 5 is a detail sectional view showing 55 a portion of the improved top or cover in a modified form of water containing chamber: otherwise it is a sectional view of Figure 1.

Referring to the drawing, the body portion 60 of the improved top or cover, comprises a sheet of fabric material of suitable texture to absorb moisture, such as canvas or the like, cut and made up to conform to 65 the shape and size of the opening of the receptacle, over which it is to be applied, as

illustrated in the drawing. In Figure 1 the cover is of circular form, and obviously of the type to be used over the top of cylindrical receptacles like the bucket, and it is 60 secured thereto by means of a draw string 2 passing through perforations 12, near the outer edge of the fabric body 1, from alternate sides of the fabric; and as the body portion 1 of the cover was cut out with 65 ample allowance of fabric to comfortably turn down over the outer edges of the opening of the receptacle 3, the valance 4 is thus formed, as illustrated in the drawing, engaging around and underneath the outer rim 70 of the opening of the receptacle 3. When the string 2 is drawn and tied fast around receptacle 3, the valance 4 may be pressed downward with the hands, stretching the 75 cover over the opening, with the result of a closure scarcely approached by metal or wood covers.

Then the contents of the receptacle are further protected by a steady supply of 80 moisture to the fabric, of which the cover is composed, as the moisture closes the pores of the fabric; and the constant evaporation lowers the temperature within the receptacle. Hence the improved top or cover is provided 85 with a water receptacle or chamber, which I have found it convenient to form as an oval shaped roll 5 extending around some portion of the fabric composing the body 1, preferably as shown in Figures 1 and 2 of the drawing. The water chamber 5 may 90 be formed in any manner preferred, as by stitching an extra piece of the fabric material to the body 1, which is a practical way of forming the required chamber 5 shown in the figures of the drawing. At some point along the water chamber 5 the opening 6 is provided for the intake of water as often as required, and it is closed by the use of any of the ordinary stoppers, as the removable cap 7.

Figure 2 of the drawing illustrates the improved top or cover as applied over the opening of a different kind of receptacle, a market or picnic basket. It also illustrates the cover provided with a modified form of the water chamber 5; or the extension of branches from the said water chamber 5, indicated by the reference number 15 in the Figure 2. The improved top or cover is adapted for use, not only on the 100 smaller receptacles, but also on receptacles of larger size, as for instance, a shipping 105

crate for fruit and produce; and for the lighter weight produce, such as lettuce and the like, a crate of considerable size can be handled easily; and for receptacles of the larger size, the top or cover for same must be enlarged proportionally, consequently there is a larger fabric surface to be supplied by moisture from the water chamber 5, hence I have provided branch water chambers 15 extending from the water chamber 5 on the body 1, shown in Figure 2, as a preferred means to facilitate the distribution of water to supply moisture for the entire fabric surface of covers of the larger type. The intake 6 may be stationed on either, or both, of the chambers, 5 and 15, as preferred.

Figure 3 of the drawing illustrates the improved top or cover applied to a cylindrical receptacle in connection with said "cooling device" indicated in the drawing by the reference number 8, and applied around the receptacle 3. The body 1 is applied over the top of the receptacle 3, and is secured thereto by means of the string 2 drawing fast the valance portion 4, engaging underneath the top portion 8^a of the "cooling device" 8, as shown in the drawing. It is obvious that the best results obtain when the receptacle is surrounded and covered by fabric material supplied with moisture for the evaporating and cooling process, and this result is obtained by the application of the improved top or cover to a receptacle in connection with the said "cooling device", as illustrated in Figure 3. The top or cover retains within the receptacle the temperature as reduced by the said "cooling device", and adds to the cooling effect, the advantage of the increased evaporating surface provided by the top or cover; the one conserves the reduced temperature effected by the other, and the result is, a lower temperature within the receptacle, from their combined application.

Occasionally it is desired to apply the improved top or cover over the ordinary metal top covering of a receptacle, to obtain the cooling effect within the receptacle. Figure 4 illustrates the improved top or cover applied to the receptacle 3 in the usual manner, but resting upon the metal top 9.

I have illustrated in Figure 5 of the drawing a modified form of construction for the water chamber 5, in which a tubular member 10 of suitable material (such as a heavier or stiffer fabric, rubber, or sheet metal) provided with a series of perforations 10^a, is inserted within the enclosure 5, thus supplying reinforcement, or a more

rigid construction of the cover, which enhances its usefulness in some conditions of its various applications. It is obvious that the operation is substantially the same as the other form of construction shown. The water percolates outward through the perforations 10^a and is absorbed by the fabric material of the cover, as with the other form of construction shown.

It will be seen, that I have thus provided a simple, inexpensive, removable and portable, top or cover, for portable receptacles, embodying the essentials of a cooling process by evaporation, when applied; that functions whether the receptacle is sitting still, or is jostled about by the motion of a vehicle or common carrier; that can be cleansed by scalding, and kept in a sanitary condition.

I have thus illustrated and described my invention in a preferred form, yet I desire the right to make such changes as may fall within the scope of the claims.

I claim:

1. A removable top or cover for receptacles, comprising a covering composed of fabric material, a part of the fabric material composing said covering being formed as a water chamber adapted to receive a supply of water and feed the same gradually to the remainder of said material.

2. A removable top or cover for receptacles, comprising a covering composed of fabric material, a part of the fabric material composing said covering being formed as a closed water chamber adapted to receive a supply of water and feed the same gradually to the remainder of said material, and a draw string threaded through the margin of said covering for securing the same to the top of the receptacle.

3. A removable top or cover for receptacles, comprising a covering composed of fabric material, a part of the fabric material composing said covering being formed as a closed water chamber, with closed branch water chambers projecting therefrom, adapted to receive a supply of water and feed the same gradually to the remainder of said material.

4. A removable top or cover for receptacles, comprising a covering composed of fabric material, a part of the fabric material composing said covering being formed as a closed water chamber, and means of reinforcement within the said closed water chamber adapted to receive a supply of water and feed the same gradually to the remainder of said material.

JOHN LEWIS TANDY.
